MEANS FOR DRAWING PARALLEL LINES

Harold L. De Lisle, Two Rivers, Wis.

Application January 21, 1938, Serial No. 186,184

2 Claims. (Cl. 33—110)

This invention relates to means for drawing parallel lines at a given distance apart and is of particular utility to draftsmen or the like.

Among other objects the invention aims to provide improved and simplified means of this character which requires a minimum of adaptation to existing drafting devices.

Other objects and advantages will be apparent from the following description taken together with the accompanying drawing, in which:

Figure 1 is a plan view of my improved means, on say full scale;

Figure 2 is an enlarged cross-section taken on the line 2—2 of Fig. 1;

Figure 3 is a bottom view of the device shown in Fig. 2; and

Figure 4 is a partial cross-section taken on the line 4—4 of Fig. 1.

Referring in detail to the illustrative construction shown in the drawing, the triangle 10 may be the usual draftsman's triangle constructed of transparent material as is well known in the art. The edges 11 and 12 may be right-angularly related one to the other, and the edge 13 a hypotenuse thereof. These edges 11, 12 and 13 may be chamfered on their under side as at 14, as best shown in Fig. 4, and as partially indicated in Fig. 1, in order to minimize danger of blurring when a pen is used with the triangle.

In addition to the usual central cut-out portion 15 of the triangle, in accordance with the present invention the triangle 10 as here shown has at least one and in this instance three relatively narrow elongated slots 16, 17 and 18, one of these slots being parallel with each of the edges 11, 12 and 13, respectively, of the triangle.

For cooperation with these slots, means, next described, are provided for moving the triangle a predetermined distance rectilinearly for the purpose of drawing a series of parallel lines 19, for example, a given distance, in this instance three-sixteenths of an inch, apart.

Further in accordance with the present invention, and as best shown in Fig. 2, a member 20 is provided for the purpose just mentioned, preferably of beetle shape, and desirably made of say cast bronze or any other suitable material having considerable weight for its size. The bottom of the member 20 is channelled as at 21, this channel being of approximately the length and width of the slots in the triangle. Reciprocally secured in the channel 21 are a pair of longitudinally aligned cylindrical feet 22, each having an extension 23 through an elongated aperture 24 of which passes a clamping screw 25. The portions 24 fit snugly

but slidingly in the channel 21 and the feet may be reciprocated in the channel limited by the relative movement of the screw 25 and elongated aperture 24. The head of the screw prevents displacement of the feet from the channel.

For purposes of reciprocating the feet 22, each of the extensions 24 of the feet, has, in this instance, a perpendicular bearing portion 26 which projects into the enlarged central recess 27 in the member 20, this recess communicating with the channel 21. The bearing portions 26 are therefore parallel and oppositely related. The rod 28 having oppositely threaded ends 28a and 28b and a central thumb-wheel 29 is supported by the bearing portions 26, each of the ends having threaded engagement with a tapped perforation in the bearing portions 26. The thumb-wheel 29 projects revolvably through an opening 30 in the member 20 opening into the top surface of this member and communicating with the recess 27, the extent of projection of the thumb-wheel into the opening being just sufficient to permit the thumb of the operator to frictionally contact the thumb-wheel, preventing axial movement of the rod 28.

By the construction just described, it will be understood that a certain degree of rotation of the thumb-wheel 29 will cause reciprocation of the feet 22 toward or away from each other to extend or contract the distance between these feet. By suitable arrangement of the pitch of the threads 28a, 28b, a given partial rotation of the thumb-wheel 29 will move the feet 22 toward or away from each other a distance of say one-sixteenth of an inch, one complete revolution of the thumb-wheel moving the feet the full distance permitted which will be say five-sixteenths of an inch. To enable the operator to determine the distance which the feet will move, the periphery of the thumb-wheel may be graduated by sixteenths of an inch as indicated at 31.

Thus, for example, when the feet are at the farthest distance apart, the thumb-wheel 29 may have its zero graduation registered with a fixed mark 32 on the body of the member 20 adjacent the opening 30. At that time the member 20 may be superposed on the triangle 10 and carried therewithin with the feet 22 received in say the slot 16 of the triangle and with the feet contacting the ends of this slot. At this time, by means of the upper edge 12 of the triangle, the uppermost of the parallel lines 19 would have been drawn. If now it be desired to draw the remainder of the parallel lines 19 and at a distance of three-sixteenths of an inch apart, the

operator may rotate the thumb-wheel 29 until the graduation on the periphery of the wheel indicating three-sixteenths of an inch is in register with the mark 32. When this has been done, the feet 22 will be drawn together a total distance of three-sixteenths of an inch.

It will be understood that the feet 22 are of sufficient depth to contact the drawing 33, through the slot 16, the amount which the feet 10 project below the body 20 being slightly greater than the thickness of the material of the triangle 10, as best shown in Fig. 2. To minimize slippage of the feet on the drawing 33 when desired to maintain them stationary, the feet 22 are undercut as at 34 to provide somewhat sharp edges 35 thereon.

Having adjusted the device 20 for successive movements of three-sixteenths of an inch, the operator next moves the device 20 downward, as 20 shown in Fig. 1, to the limit of its movement in the slot 16, as would be determined by abutment of the lowermost foot 22 with the lowermost end of the slot 16. This may be done with the left hand of the operator while maintaining the 25 triangle stationary with the right hand. Thereupon, while maintaining with the left hand the device 20 stationary with respect to the drawing 33, the operator moves the triangle 10, with the right hand, downward a distance limited by the 30 play of the feet 22 in the slot 16 which in this instance has been predetermined to be three-sixteenths of an inch. At this time the uppermost foot 22 is in contact with the uppermost end of the slot 16 as shown in Fig. 1. By holding 35 the device 20 stationary with the left hand the triangle 10 is also held stationary from any downward movement, and its edge 12 is parallel with, but three-sixteenths of an inch downward from the uppermost parallel line 19, whereupon the 40 operator draws another of these parallel lines. Then the operator again moves the member 20 downwardly in the slot 16 to the limit of its movement while maintaining the triangle stationary, and then holds the member 20 stationary while 45 moving the triangle downward to the limit of its movement, whereupon another parallel line 19 may be drawn similarly spaced from the next uppermost line. This may be repeated until the 50 number of parallel lines desired has been drawn.

It will be understood that the member 20 may be used with any one of the slots 16, 17 or 18 and for a similar purpose to that just described.

In order to place a tension upon the thumb-wheel 29 and prevent accidental displacement 55 thereof, the compression coil spring 36 may be disposed between the thumb-wheel and one of the bearing portions 26.

In order to reduce the contacting surface area

of the triangle, the triangle is desirably recessed on its faces, in addition to the cut-outs already referred to, by grooves 100 along the margins of the triangle. As so reduced, the area of the triangle which contacts with the drawing or 5 tracing is so diminished as to minimize blurring of the drawing by the triangle or friction therebetween which has heretofore been inherent in the devices of the prior art. To prevent the 10 grooves 100 from forming suction cups, they desirably are vented as at 101, in this instance, to the cut-out portions 16, 17, or 18 as the case may be. It will be understood that the grooves 100 may be along each margin of the triangle and 15 on both faces.

Having described my invention, I claim:

1. In a device of the class described, the combination with a draftsman's triangle or the like, having a relatively narrow elongated slot therein, of a member separable therefrom of greater 20 area than said slot superposed thereabove within the area of the triangle and having a pair of feet receivable in said slot and projecting below the lower face of the triangle and means carried by the member for extending or contracting 25 the distance between the said feet within the limits of said slot, said member being of somewhat heavy beetle-like formation extending well above said triangle to be readily grasped by the draftsman.

2. In a device of the class described for use with a draftsman's triangle or the like, the combination of a relatively heavy body having a central recessed portion and a pair of longitudinally extending aligned oppositely directed channels in 35 its lower flat face opening into said recessed portion, a pair of feet for said body each foot having a flat extension snugly slidably in one of said channels and having an elongated aperture therein, a clamping screw passing through each 40 aperture into said body, the said foot extensions having perpendicularly directed bearing portions disposed in parallel within said central recess, tapped perforations in said bearing portion, a threaded rod passing through both said perforations and having a thumb-wheel fixed thereon, an opening from said recess through the upper 45 surface of said body receiving the periphery of said thumb-wheel therethrough and a compression coil spring disposed on said rod between said thumb-wheel and one of said bearing portions to apply friction between said rod and said bearing portion whereby the thumb-wheel may be turned from the upper surface of said body to extend or contract the distance between said 50 feet.

HAROLD L. DE LISLE.
